A. J. PRANCE.
SCREW CUTTING DIE.
APPLICATION FILED JULY 12, 1916.

1,255,223.

Patented Feb. 5, 1918.

UNITED STATES PATENT OFFICE.

ALBERT J. PRANCE, OF DETROIT, MICHIGAN, ASSIGNOR TO MURCHEY MACHINE AND TOOL COMPANY, OF DETROIT, MICHIGAN, A CORPORATION OF MICHIGAN.

SCREW-CUTTING DIE.

1,255,223.

Specification of Letters Patent.

Patented Feb. 5, 1918.

Application filed July 12, 1916. Serial No. 108,785.

To all whom it may concern:

Be it known that I, ALBERT J. PRANCE, a citizen of the United States, residing at Detroit, in the county of Wayne and State of Michigan, have invented new and useful Improvements in Screw-Cutting Dies, of which the following is a specification.

This invention relates to screw-cutting dies, and more particularly to that class thereof, in which the thread-cutting devices or "chasers" are automatically released from the work at a predetermined point of the operation.

The invention has for one of its objects the provision of an instrument of the kind named comprising a rotatable beveled adjusting collar co-operative with the chasers for precisionizing their position diametrically of the work. The invention has, furthermore, for its object the improved construction of the slidable chaser-carrying head which is moved forward by the chasers cutting their way into the work even after the shank of the instrument has been stopped against advancing, this continued advance of the head allowing the chasers to suddenly free themselves from the work. Further objects of this invention will hereinafter appear and be particularly defined in the claims.

The invention has been clearly illustrated in the accompanying drawings, in which similar characters denote similar parts, and in which—

Figure 1 is a front view of my improved device.

Fig. 2 is a side view of the same.

Fig. 3 represents a longitudinal section on line 3—3 of Fig. 1.

Fig. 4 shows a fragmentary outside view of the slidable head, looking in the direction of arrow 4 of Fig. 3.

Fig. 5 is a longitudinal section on line 5—5 of Fig. 1, illustrating the parts in "closed-in" position.

Fig. 6 is a front view taken on line 6 of Fig. 5.

Fig. 7 is a cross-section on line 7—7 of Fig. 5, and Fig. 8 illustrates the outer shell, looking in the direction of arrow 8 of Fig. 7.

Referring to the drawings, 10 denotes the shank portion of the device adapted to be secured in the turret of a lathe and having a flange 11 and carrying a head 13 provided

with a pair of driving pins 12 for holding the main body against rotation, without however interfering with any longitudinal movement relatively to the shank, the pins entering suitable recesses 14 in the body (see Figs. 3 and 7). The front face of the flange disk 11 has also a steady-stud 15 for maintaining the head 13 and the shank in central relation with each other, said stud entering a central longitudinal aperture 16 in the head.

The head 13 carries in its front face a plurality of progressively-cut chasers or threading tools 17 adapted for radial adjusting movement, each chaser having a backing face 17^a (see Fig. 3) which engages, when in cutting position (see Fig. 5), the inner face of a hardened wearing block 18, all the several blocks being thus surrounded and engaged at their outer faces by an annulus 19. The front faces of the several chasers and the head 13 are flush, the chasers being set into slots (see Fig. 6) so that a cover plate 20, screwed to the head by screws 21, will hold these parts together. Each chaser is normally pushed outward against its wearing-block 18 by one end of a lever 22 lying within a longitudinal slot 23 provided therefor in the head, and having its pivot 24 so disposed as to establish on said lever a tail-portion 22^a, which, when the front end of the lever is pushed outward by a spring 25 carried by the head, will serve to limit the outward movement of the lever. By referring to Fig. 5 it will be seen that the chaser has an aperture 26 to receive the lever-end.

The several wearing-blocks are seated in suitable cut-out portions 27 (see Fig. 2) provided in the front end of a shell 28 which incloses the several parts thus far mentioned excepting the blocks which are free to be moved radially within the cuts 27 but are held against frontwise longitudinal movement by virtue of lips 29, as shown.

The several wearing blocks 18 may be positively moved radially inwardly or be permitted to move outwardly, as desired, for the purpose of precisionizing the opening between the chasers in conformity with a certain diameter of thread to be cut. For this reason each block has a cone-face or bevel 18^a, all of these faces being engaged

by the correspondingly-shaped inner face of the annulus 19 above referred to, this annulus having a screw-threaded connection with the shell 28 so that it may be rotated thereon to move longitudinally and thus move the blocks toward or away from each other, according to the direction of rotation.

In order to preserve the radial alinement between each chaser and its wearing block, 10 the shell 28 and head 13 are keyed together by pin-and-slot construction 30 (see Fig. 8).

It will now be seen that, when the several parts are in their closed-in positions shown in Fig. 5, and the annulus 19 is then 15 rotated by hand so as to move the same forward on the shell 28, the several chasers will be moved outwardly, due to the co-operative bevel faces of the annulus and wearing blocks. A rotation of the annulus 20 causing a movement toward the rear of the head will cause the chasers to be moved toward each other. The amount of such radial or inward adjusting movement may be read on the front face of the device, 25 the annulus having a series of graduations to be read in conjunction with an index pointed *i* on the stationary cover plate (see Fig. 1). The linear pitch of the screw thread and the bevel of the wearing blocks 30 are preferably so proportioned that a rotation of the annulus for an amount equal to one graduation-division will move the chasers radially for one-thousandth of an inch.

35 The device, when in use, is secured with its shank in the turret of a lathe. The rod to be screwthreaded is clamped into the spindle of the lathe head, and the turret slide is then moved toward the lathe head until the 40 chasers have commenced to cut. After that the advance movement of the turret slide depends upon speed with which the screw-threads are cut, as usual in machines of this class. As soon as the advance movement of 45 the turret slide is stopped, either by stop member on the lathe-bed or otherwise, the continued screw-cutting operation on the work will still continue to advance the chasers and with them the head 13 of the 50 device, until this continued advance movement has proceeded far enough to bring the backing-faces 17^a of the chasers from underneath the wearing-blocks 18. By referring to Figs. 3 and 5 it will be noted that each 55 chaser has a beveled drop-off face 17^b, so that, as soon as the front edge of said beveled face has passed beyond the front edge of its wearing block, the spring 25 and lever 22 can then become effective in "opening" the 60 chaser and thus quickly release it from the work, it being self evident that this outward movement of the chasers will also result in moving the several wearing-blocks, together with their carrying shell 28 and the annulus 65 19 slightly rearward relatively to the chasers.

The length of the cutting operations can therefore be accurately gaged.

Means are also provided for opening or closing the chasers by hand, these means consisting preferably of a hand lever 35 70 passing through an aperture 36 in the shell 28 and having its lower end secured in a tilting block 37 which is pivotally seated, as at 38, within a recess 39 of the head-member 28. It will be readily understood that by throwing the lever 35 from right to left, in Fig. 3, the head and shell will assume the positions shown in Fig. 5, in which the chasers are "closed-in", ready to work.

I claim:

1. A screw-cutting die comprising a head, 80 chasers carried thereby, each chaser having an aperture, and means for precisionizing the positions of said chasers radially, said means consisting of a shell surrounding said head, an annulus carried by said shell and having an inner beveled face, and means for moving said annulus on the shell longitudinally, and spring-actuated levers pivoted in the head and having their front ends disposed within said chaser apertures, for opening the chasers at a predetermined point of the advance movement of the head relatively to the shell.

2. A screw-cutting die comprising a head, 95 chasers carried thereby, and means for precisionizing the positions of said chasers radially, said means consisting of a shell surrounding said head, an annulus carried by said shell and having an inner beveled face, 100 and means for moving said annulus on the shell longitudinally, and independent spring-actuated levers pivoted in the head and removably engaging said chasers, for opening the chasers by the advance movement of the head relatively to the shell, and means for 105 limiting the outward movement of said levers to maintain said chasers in the head subsequently to their clearing the shell.

3. A screw-cutting die comprising a head, 110 chasers carried by said head and each having a recess in its rear face, and means for precisionizing the position of said chasers radially, said means consisting of a shell surrounding said head, an annulus carried by 115 the shell and having an inner beveled face, spring-actuated levers pivoted in the head and having tail pieces for limiting the outward movement of said levers, the forward ends of said levers entering said recesses of 120 the chasers, respectively.

4. A screw-cutting die comprising a shell having cut-out portions in its front end, 125 wearing blocks radially movable in said cut-out portions and each having an outer beveled face, means for locking said blocks against longitudinal movement in the shell, a head slideable in the shell, means for locking said shell and head against rotation relatively to each other, chasers carried by 130

5 said head and radially movable therein, an annulus carried by said shell and having an inner beveled face coöperative with the beveled outer faces of the wearing blocks respectively, and means for moving said annulus on the shell longitudinally.

6. A screw-cutting die comprising a shell, wearing blocks radially movable therein, and each having an outer beveled face, a head 10 slidable within said shell, chasers radially movable in said head and each having a backing face engaging said wearing blocks, an annulus carried by said shell and having an inner beveled face coöperative with the 15 beveled outer faces of said wearing blocks, said annulus being in screw-threaded engagement with said shell for moving the same longitudinally thereon.

7. A screw-cutting die comprising a head,

chasers carried thereby and movable radially 20 therein, each chaser having a drop-off face, a shell surrounding said head and having in its surrounding wall an aperture, an annulus carried by and movable on said shell for variably limiting the outward movement 25 of said chasers, blocks carried by said shell and holding said chasers in closed-in positions, a tiltable lever pivotally seated in the head and passing through said aperture for moving said head relatively to the shell to 30 open or close the chasers.

In witness whereof I hereunto subscribe my name in the presence of two witnesses.

ALBERT J. PRANCE.
